UNITED STATES PATENT OFFICE.

CHARLES C. SCHNEIDER, OF ST. LOUIS, MISSOURI, ASSIGNOR TO JAMES H. CUTTER, OF ST. LOUIS, MISSOURI.

CATCHING DEVICE FOR CLOTH-PILEING MACHINES.

1,308,766.

Specification of Letters Patent.

Patented July 8, 1919.

Application filed July 23, 1917. Serial No. 182,366.

To all whom it may concern:

Be it known that I, CHARLES C. SCHNEIDER, a citizen of the United States, and resident of St. Louis, Missouri, have invented certain new and useful Improvements in Catching Devices for Cloth-Piling Machines, of which the following is a specification.

This invention relates to improvements in catching devices for cloth piling machines and has for its object a mechanism located on a table upon which the cloth piling machine operates for supporting the ends of the cloth while the machine which carries the cloth to be piled is being propelled backwardly and forwardly upon the table.

A further object of my invention is to provide means which are automatically operated upon contact by a cloth piling machine comprising a pair of supporting rods arranged to enter the end fold of the cloth and support the same while the piling machine is being moved.

A further object of my invention is to construct a catching device, which is arranged adjustably, vertically as well as horizontally so as to accommodate various widths of cloth as well as to be regulated to conform with the pile of cloth as the same increases in height.

A further object is to provide a means whereby a pair of coacting cloth supporting rods and their actuating mechanisms are raised simultaneously for proper relation to the progressively increasing height of the pile of cloth laid on the table by a piling machine.

Figure 1 is a side elevation of a table with my improved catching device located in position thereon showing its operative relation with the cloth piling machine.

Fig. 2 is a top plan view of the catching mechanism.

Fig. 3 is fragmental side elevation showing the supporting post in section and the catching mechanism in relative position with the piling machine.

Fig. 4 is a detail view of the supporting bar which forms a part of the catching mechanism.

Fig. 5 is a top plan view of one of the cloth supporting rods.

Fig. 6 is a similar view to Fig. 5 showing the cloth supporting rod in released position.

Fig. 7 is a sectional view taken on the line 7—7 of Fig. 6.

Fig. 8 is a detail perspective view of the

gear, which forms a part of the catching mechanism.

Fig. 9 is a detail horizontal sectional view of one of the posts in which the catching device is supported.

Fig. 10 is a detail top plan view of one of the posts.

Fig. 11 is a detail perspective view of the tripping lever made use of in connection with my invention.

Fig. 12 is a detail sectional view of a portion of the operating shaft and the worm mounted thereon.

Fig. 13 is a detail perspective view of a portion of the supporting bar and the sliding post.

Referring to the drawings in detail, 14 indicates a table and 15 a cloth piling machine located thereon. On the table is located my improved catching device 16 against which the cloth piling machine contacts, operating the same. My improved catching device comprises an angle bar or support 17 disposed transversely of the table, its one end being provided with a hook 18 which fits around one side margin of the table top, and the other end of the bar is clamped against the table top by an ordinary clamp 19. To the angle bar 17 is attached a pair of hollow posts 20, the same being slotted as indicated by the numeral 21 and provided with projecting flanges 22 so as to act as supports and proper guides for supporting brackets 23. The brackets 23 are each provided with an internally screwthreaded enlargement 24 of a size to snugly fit within the hollow post and through the enlargement is passed a screw 25, having its upper end connected with a worm gear or wheel 26, and by the rotation of the screw, the bracket 23 is raised and lowered to correspond with the height of the pile of cloth upon the table. The posts are each provided with projecting perforated lugs 27 through which is passed a shaft 28, and upon said shaft between the lugs are located worms 29 and 30. The post provided with the worm 29 is secured rigidly to the angle bar, while the post carrying the worm 30 is adjustably mounted thereon.

To provide for the proper adjustment of this post 30, I provide the angle bar with a slot 31, the post being provided with a rectangular lug 32 which fits into the slot 31 and the said post is retained in its set position by means of the bolt 33. The shaft 28

14 15 16 17 18 19 20 21 22 23 24 25 26 27 28 29 30 31 32 33 34 35 36 37 38 39 40 41 42 43 44 45 46 47 48 49 50 51 52 53 54 55 56 57 58 59 60 61 62 63 64 65 66 67 68 69 70 71 72 73 74 75 76 77 78 79 80 81 82 83 84 85 86 87 88 89 90 91 92 93 94 95 96 97 98 99 100 101 102 103 104 105 106 107 108 109 110

is provided with a key way 34, and the worm 30 with a key 35, whereby the worm 30 may freely slide upon its shaft during an adjustment of the post upon the angle bar, and the shaft 28 be capable at all times of raising and lowering the brackets simultaneously by manual operation of the crank 36.

Each of the brackets 23 is provided with a mutilated gear wheel held by the bolt 38 and also a lever 39, whose short end is designed to contact with a recess 41 formed in the mutilated gear, and when said lever is so placed, the gear is held in locked position. This gear is provided with a projecting arm 42, which is so located as to project parallel with the angle bar when the gear is in its locked position (see Fig. 5).

The bracket 23 is provided with a housing 43 in which is seated a rack bar 44, the teeth of said rack bar meshing with the teeth on the gear, the forward end of the rack being suitably bent as indicated by the numeral 45, and against which the forward end of the piling machine 15 contacts. The under side of the housing is provided with a projection 46 to which one end of the spring 47 is attached, the other end of said spring being attached to a projection 48 secured to the opposite end of the rack bar. The tendency of said spring is to return the rack bar to its normal position after the aforesaid spring has been compressed by the contacting of the machine.

The lever 39 is contacted with by the front end of the piling machine slightly in advance of the machine contacting with the rack bars so that its short end is released from the recess 41 which will then permit the arm 42 to assume a position as shown in Fig. 6, and when in this position the cloth carried by the piling machine is so positioned as to form a loop in the cloth permitting the arms 42 to enter the fold or loop immediately upon moving the machine away from the catching device. The lever 39 is controlled or placed in its normal position by means of the spring 49.

The mutilated gear 37 is provided with an inclined shoulder over which the short arm 40 of the lever rides when the lever is placed rearwardly so as to allow the gear to operate simultaneously with the contacting of the end of the rack bar 45, also to permit the short arm or tooth to be properly guided into the recess when the arm 42 is returning to its normal position.

One relative position of the catching devices is shown in Fig. 2, together with the means whereby they can be adjusted horizontally on the table to accommodate various widths of cloth.

The essential feature of applicant's device is to construct a catching device arranged to be adjustable horizontally.

I may, if desired, dispense with the use of the shaft and worms and in the place of the worm gear 26 place a hand wheel so that both posts can be operated independently if so desired.

Having thus fully described my invention, what I claim is:

1. A catching device for cloth piling machines comprising a supporting bar mounted upon a table, a stationary post and a sliding post connected to the supporting bar, brackets carried by the posts, means for adjusting the brackets in the posts vertically, cloth supporting rods mounted on the brackets, means for operating the same when contacted with by the piling machine and a lever mechanism for locking the rods in their normal position, substantially as specified.

2. A catching device for cloth piling machines comprising a bar, a pair of posts supported thereby, a bracket mounted in each post, a cloth supporting rod carried by each bracket, means for relatively adjusting the posts to accommodate different widths of cloths, means for adjusting the brackets vertically to progressively position the cloth supporting rods at heights varying as the cloth is piled, an automatic means for operating the cloth supporting rods to functionate and non-functionate positions, comprising rack bars arranged for movements in one direction by contacting with the piling machine, gears meshing with the rack bars to swing the rods as the rack bars are moved by the machine, springs acting in opposition to the rack bars and gears, and spring actuated levers arranged in the path of the machine forming automatic locks for the cloth supporting rods.

3. A device of the class described comprising a catching device composed of a stationary member and an adjustable member, cloth supporting arms carried by each of the members, a worm mechanism for adjusting the cloth supporting arms vertically, means for operating the same, and means for locking the cloth supporting arms in their normal position, substantially as specified.

In testimony whereof, I have signed my name to this specification in presence of two subscribing witnesses.

CHARLES C. SCHNEIDER.
